FIREARM

Melvin M. Johnson, Jr., Brookline, Mass., assignor
to: Melvin M. Johnson, Brookline, Edward E.
Rice, Boston, Mass., and himself, as trustees of
the Johnson Patent Trust, Boston, Mass.

Application July 1, 1944, Serial No. 543,113

8 Claims. (Cl. 42-4)

This invention relates to firearms of the type having a reciprocating bolt which rotates into and out of locking position at the forward end of its stroke, and more particularly to firearms of the type in which the unlocking of the bolt is effected by a short recoil movement of the barrel and in which the recoil spring acts on the bolt through a pusher having a cam surface which cams the bolt into locked position at the forward end of its stroke, as in prior patents, 2,094,156; 2,146,743 and 2,215,470.

In firearms of this type there is a tendency for the bolt and pusher to rebound when they reach forward position and the principal object of the present invention is to provide means for preventing this rebound which is simple and reliable in action and which does not interfere materially with the recoil of the bolt when the gun is fired.

For the purpose of illustration a typical embodiment of the invention is shown in the accompanying drawing in which

Fig. 1 is a side elevation;

Fig. 2 is a section on line 2—2 of Fig. 1;

Fig. 3 is a top plan view of the central portion of the firearm; and

Fig. 4 is a top plan view of the bolt and pusher, showing in broken lines the improved means for preventing rebound.

The particular embodiment of the invention chosen for the purpose of illustration is a firearm of the type disclosed in the aforesaid patents comprising a receiver 1 having two tubes 2 and 3 threaded into its rearward end, the upper tube holding the recoil spring and the lower tube constituting a compartment for repair tools or the like, a shoulder-piece 4 which also serves as a cover for the rear ends of the aforesaid tubes, the cover being pivoted at 6 to swing upwardly out of line with the rear ends of the tubes, a recoil-barrel 7, a shield 8 surrounding the rear end of the barrel, a fore grip 9 pivotally mounted on the forward end of the shield, a magazine 11, a bolt 12 and a pusher 13, the bolt 12 having an actuating handle 14 projecting outwardly through a slot 15 in the right-hand side of the receiver for use in manually retracting the bolt. The forward end of the slot is wider to form an ejection opening 16. Opposite this opening is an ejector 20 (Fig. 2). The recoil spring 17 extends forwardly around the rear end of the pusher 13, seating against a shoulder 18 on the pusher. The pusher 13 is provided with a vertical slot 19 to accommodate the hammer and the firing pin 21 projects rearwardly from the bolt into this slot. The pusher 13 is provided with an ex-

tension 22 which projects forwardly over the bolt and is provided at its forward end with a cam surface 23. This extension carries a roller 24 which projects upwardly into a slot 26 in the top of the receiver to prevent rotation of the pusher. The bolt 12 is also provided with an upward projection 27 having a cam surface 28 engageable with the surface 23 and another cam surface 29 engageable with the cam surface 31 on the receiver. The projection 27 also carries a roller 32 to ride in the groove 26 while the bolt is reciprocating back and forth. At its forward end the bolt is provided with an annular row of locking lugs 33 engageable behind locking lugs in the barrel. Details of construction of the various parts of the firearm are disclosed in co-pending applications Serial Numbers 548,040, 548,041 and 548,042, filed August 4, 1944.

As shown in Fig. 3 there is a slight clearance 20 between the cam surfaces 29 and 31 when the bolt is in its forward locked position. Thus when the gun is fired the bolt and barrel recoil together for a short distance. When the surface 29 on the bolt strikes the surface 31 on the receiver the bolt is rotated in a counterclockwise direction, thereby unlocking the bolt from the barrel. The bolt then continues its recoil alone, the roller 32 passing into the groove 26 in the top of the receiver to keep the bolt from rotating while it is moving back and forth. As the bolt returns to its forward position the roller 32 leaves the groove 26, the bolt then being free to be rotated clockwise in the locked position. This rotation into locked position is effected by the cam surface 23 of the pusher pressing against the cam surface 28 of the bolt. This rotary movement of the bolt not only brings the locking lugs 33 behind the lugs on the barrel but it also brings the cam surface 29 of the bolt in line with the cam surface 31 on the receiver. Thus when the trigger is again pulled this cycle of operations is repeated. Inasmuch as the foregoing construction and mode of operation is described in detail in the aforesaid patents, further description is 45 unnecessary here.

Under the influence of the recoil spring 17 the bolt arrives at its forward locked position with considerable impact. Consequently it tends to rebound in a counterclockwise direction. According to this invention the rebound is counteracted by a pawl 36 which is pivoted at 37 between two ears 38 on the left-hand side of the receiver. A spring 39 urges the rearward end of the pawl outwardly, thereby forcing the forward end of the pawl inwardly against the roller 24 on the

pusher. Inasmuch as the counterclockwise rebound of the bolt tends to urge the pusher rearwardly, through the cam surfaces 23 and 28, the rebound is yieldingly counteracted by the pawl 36. However the forward end 41 on the pawl is inclined sufficiently to be cammed out of the path of the roller 24 when the gun is fired. As the bolt and pusher arrive at the forward position shown in Figs. 3 and 4 the pawl 36 snaps behind the roller 24 to prevent the aforesaid rebound.

It should be understood that the present disclosure is for the purpose of illustration only and that this invention includes all modifications and equivalents which fall within the scope of the appended claims.

I claim:

1. A firearm of the type having a short recoil movement of the barrel, a reciprocating bolt which rotates into and out of locked position at the forward end of its reciprocatory movement, the bolt having locking lugs and a rearwardly facing cam surface, a forwardly facing cam in the path of said bolt surface for rotating the bolt into unlocked position during said short recoil, a recoil spring, a reciprocatory pusher interposed between the spring and bolt with a forwardly facing cam for rotating the bolt into locked position as the bolt approaches the forward end of its recoil movement, the pusher having a rearwardly facing abutment, and a spring detent which snaps behind said abutment when the pusher reaches the forward end of its recoil movement, thereby to restrain rebound of both the pusher and bolt.

2. A firearm of the type having a short recoil movement of the barrel, a reciprocating bolt which rotates into and out of locked position at the forward end of its reciprocatory movement, the bolt having locking lugs and a rearwardly facing cam surface, a forwardly facing cam in the path of said bolt surface for rotating the bolt into unlocked position during said short recoil, a recoil spring, a reciprocatory pusher interposed between the spring and bolt with a forwardly facing cam for rotating the bolt into locked position as the bolt approaches the forward end of its recoil movement, the pusher having a rearwardly facing abutment, and a spring detent which snaps behind said abutment when the pusher reaches the forward end of its recoil movement, the engaging surface of the detent being inclined sufficiently to cam out of the path of the abutment when the bolt recoils.

3. A firearm of the type having a short recoil movement of the barrel, a receiver, a reciprocating bolt which rotates into and out of locked position at the forward end of its reciprocatory movement, the bolt having locking lugs and a rearwardly facing cam surface, the receiver having a forwardly facing cam surface in the path of said bolt surface for rotating the bolt into unlocked position during said short recoil, a recoil spring, a reciprocatory pusher interposed between the spring and bolt with a forwardly facing cam for rotating the bolt into locked position as the bolt approaches the forward end of its recoil movement, the pusher having a guide projecting radially into a guideway in the receiver to restrain rotation of the pusher, and a spring detent which snaps behind said guide when the pusher reaches the forward end of its recoil movement, thereby to restrain rebound of both the pusher and the bolt.

4. A firearm of the type having a short recoil movement of the barrel, a receiver, a reciprocating bolt which rotates into and out of locked posi-

tion at the forward end of its reciprocatory movement, the bolt having locking lugs and a rearwardly facing cam surface, the receiver having a forwardly facing cam surface in the path of said bolt surface for rotating the bolt into unlocked position during said short recoil, a recoil spring, a reciprocatory pusher interposed between the spring and bolt with a forwardly facing cam for rotating the bolt into locked position as the bolt approaches the forward end of its recoil movement, the pusher having a guide projecting radially into a guideway in the receiver to restrain rotation of the pusher, and a spring detent which snaps behind said guide when the pusher reaches the forward end of its recoil movement, the engaging surface of the detent being inclined sufficiently to cam out of the path of the guide when the bolt recoils.

5. A firearm of the type having a short recoil movement of the barrel, a receiver, a reciprocating bolt which rotates into and out of locked position at the forward end of its reciprocatory movement, the bolt having locking lugs and a rearwardly facing cam surface, the receiver having a forwardly facing cam surface in the path of said bolt surface for rotating the bolt into unlocked position during said short recoil, a recoil spring, a reciprocatory pusher interposed between the spring and bolt with a forwardly facing cam for rotating the bolt into locked position as the bolt approaches the forward end of its recoil movement, said receiver having a longitudinal guideway along the bolt chamber, a roller mounted on the pusher to project into the guideway to restrain rotation of the pusher, and a spring detent which engages behind said roller when the pusher reaches the forward end of its recoil movement.

6. A firearm of the type having a short recoil movement of the barrel, a receiver, a reciprocating bolt which rotates into and out of locked position at the forward end of its reciprocatory movement, the bolt having locking lugs and a rearwardly facing cam surface, the receiver having a forwardly facing cam surface in the path of said bolt surface for rotating the bolt into unlocked position during said short recoil, a recoil spring, a reciprocatory pusher interposed between the spring and bolt with a forwardly facing cam for rotating the bolt into locked position as the bolt approaches the forward end of its recoil movement, said receiver having a longitudinal guideway along the bolt chamber, a roller mounted on the pusher to project into the guideway to restrain rotation of the pusher, and a spring detent which engages behind said roller when the pusher reaches the forward end of its recoil movement, the engaging surface of the detent being inclined sufficiently to cam out of the path of the roller when the bolt recoils.

7. A firearm of the type having a short recoil movement of the barrel, a receiver, a reciprocating bolt which rotates into and out of locked position at the forward end of its reciprocatory movement, the bolt having locking lugs and a rearwardly facing cam surface, the receiver having a forwardly facing cam surface in the path of said bolt surface for rotating the bolt into unlocked position during said short recoil, a recoil spring, a reciprocatory pusher interposed between the spring and bolt with a forwardly facing cam for rotating the bolt into locked position as the bolt approaches the forward end of its recoil movement, said receiver having a lon-

itudinal guideway along the bolt chamber, a roller mounted on the pusher to project into the guideway to restrain rotation of the pusher, and a spring detent which engages behind said roller when the pusher reaches the forward end of its recoil movement, the engaging surface of the detent being inclined sufficiently to cam out of the path of the roller when the bolt recoils, the detent comprising a pivoted pawl extending lengthwise of the bolt with its forward end swinging into and out of restraining position behind said abutment.

8. A firearm of the type having a short recoil movement of the barrel, a receiver, a reciprocating bolt which rotates into and out of locked position at the forward end of its reciprocatory movement, the bolt having locking lugs and a rearwardly facing cam surface, the receiver having a forwardly facing cam surface in the path of said bolt surface for rotating the bolt into unlocked position during said short recoil, a

recoil spring, a reciprocatory pusher interposed between the spring and bolt with a forwardly facing cam for rotating the bolt into locked position as the bolt approaches the forward end of its recoil movement, said receiver having a longitudinal guideway along the bolt chamber, a roller mounted on the pusher to project into the guideway to restrain rotation of the pusher, and a spring detent which engages behind said roller when the pusher reaches the forward end of its recoil movement, the engaging surface of the detent being inclined sufficiently to cam out of the path of the roller when the bolt recoils, the detent comprising a pivoted pawl extending lengthwise of the bolt with its forward end swinging into and out of restraining position behind said abutment and said forward end being inclined sufficiently to cam out of the path of the abutment when the bolt recoils.
